CLAIM

The ornamental design for a subsea valve actuator, as shown and described.

DESCRIPTION

FIG. 1 is a front perspective view of a subsea valve actuator showing our new design;

FIG. 2 is a rear perspective view of the subsea valve actuator of FIG. 1;

FIG. 3 is a right side elevational view of the subsea valve actuator of FIG. 1;

FIG. 4 is a left side elevational view of the subsea valve actuator of FIG. 1;

FIG. 5 is a front side elevational view of the subsea valve actuator of FIG. 1;

FIG. 6 is a rear side elevational view of the subsea valve actuator of FIG. 1;

FIG. 7 is a top plan view of the subsea valve actuator of FIG. 1; and,

FIG. 8 is a bottom plan view of the subsea valve actuator of FIG. 1.

The broken lines shown in the drawings illustrate portions of the subsea valve actuator that form no part of the claimed design.
